[57] CLAIM

The ornamental design for a bicycle rack, as shown and described.

DESCRIPTION

FIG. 1 is a perspective view of a bicycle rack embodying my new design;

FIG. 2 is a side elevational view of the bicycle rack of FIG. 1;

FIG. 3 is a front elevational view of the bicycle rack of FIG. 1, the rear elevational view being identical thereto;

FIG. 4 is a top plan view of the bicycle rack of FIG. 1;

FIG. 5 is a perspective view of a bicycle rack in accordance with a second embodiment of my new design;

FIG. 6 is a side elevational view of the bicycle rack of FIG. 5, taken from the left-hand side with respect to FIG. 5, the right-hand side elevational view being a mirror image thereof;

FIG. 7 is a front elevational view of the bicycle rack of FIG. 5;

FIG. 8 is a top plan view of the bicycle rack of FIG. 5; and

FIG. 9 is a rear elevational view of the bicycle rack of FIG. 5.

FIG. 1

FIG. 2

FIG. 3

FIG. 4

FIG. 5

FIG. 6

FIG. 7

FIG. 8

FIG. 9
